Filed May 29, 1959, Ser. No. 56,140

Term of patent 14 years

(Cl. D67—2)

FIG. 1.

FIG. 2.

FIG. 3.

FIG. 4.

Figure 1 is a perspective view of an ice cream freezer, showing my new design;

Figure 2 is a bottom plan view of the ice cream freezer shown in Figure 1, on a reduced scale;

Figure 3 is a top plan view thereof; and

Figure 4 is a side view of the ice cream freezer, portions being broken away in order to better illustrate configurational details of the motor unit and container element.

I claim:

The ornamental design for an ice cream freezer, as shown.
